UNITED STATES PATENT OFFICE.

ANTON MODRAY, OF ST. LOUIS, MISSOURI, ASSIGNOR TO ST. LOUIS BRASS MANUFACTURING COMPANY, OF ST. LOUIS, MISSOURI, A CORPORATION OF MISSOURI.

LIGHTING-FIXTURE.

1,251,406.

Specification of Letters Patent. Patented Dec. 25, 1917.

Application filed March 1, 1916. Serial No. 81,310.

To all whom it may concern:

Be it known that I, ANTON MODRAY, a subject of the Emperor of Austria, residing at the city of St. Louis, State of Missouri, have invented a certain new and useful Lighting-Fixture, of which the following is such a full, clear, and exact description as will enable any one skilled in the art to which it appertains to make and use the same, reference being had to the accompanying drawings, forming part of this specification.

The object of my invention is to produce a wall or ceiling fixture for electric light, which will be easy of assembly and insulation, and which has concealed shade supporting means of simple and efficient construction. Further objects and advantages of the invention will appear from the following detailed description.

20 In the accompanying drawings, which illustrate one embodiment of my invention, Figure 1 is a cross-sectional view of one form of my improved fixture; Fig. 2 is a bottom plan view and Fig. 3 is a side elevation 25 of the lamp socket shown in Fig. 1.

1 represents a canopy or wall-plate which may be of glass, porcelain or other suitable material, and may be attached in any suitable manner to the ceiling or wall, for example, by means of screws (not shown). The canopy is provided with a central opening through which a lamp receiving shell 3 of a socket extends. The base 2 of this socket is within the canopy and bears upon 35 the inner surface thereof adjacent to the opening. The lamp receiving shell 3 is threaded interiorly and exteriorly, and the insulating member 4, which is also threaded interior and exteriorly, is adapted to 40 screw over the shell 3, and is provided with a shoulder to bear upon the exterior surface of the canopy, whereby the base 2 and the member 4 are clamped together over the edge of the canopy opening. A threaded 45 shade supporting member 5 is adapted to screw over the insulating member 4, and, by means of the shoulder shown, to clamp the shade 8 against the exterior of the canopy.

In order to prevent the base 2 of the 50 socket from turning when the lamp 4 is being turned into position, the interior of

the canopy is provided with a recess 6 into which a projection 7 on the base 2 enters.

In the assembly and insulation of the fixture, above described, the line wires may 55 be connected to the socket and the socket then placed in position in the canopy and clamped there by means of the insulating member 4. The canopy is then attached to the wall or ceiling, after which the shade 60 is secured in position by means of the member 5. It will be noted that all the parts are securely and firmly positioned, and that the shade support is concealed.

Having fully described my invention 65 what I claim as new and desire to secure by Letters Patent of the United States, is:

1. In a lighting fixture, the combination of a canopy or wall-plate having a central opening, a lamp socket bearing against the 70 inner surface of said canopy and having an exteriorly and an interiorly threaded lamp receiving shell extending through the opening in the canopy, an exteriorly and interiorly threaded supporting member adapted 75 to screw over the exterior of the lamp receiving shell and provided with a shoulder to bear upon the exterior surface of the canopy, a lamp shade, and a threaded shade supporting member adapted to screw 80 over the first named supporting member and clamp the shade against the canopy.

2. In a lighting fixture, the combination of a canopy or wall-plate having an opening, a lamp socket having its base bearing 85 on the interior of the canopy adjacent to said opening and an exteriorly and interiorly threaded shell extending through the opening, a clamping member adapted to be screwed over the shell and having exterior 90 threads, and means adapted to screw over said last named member and form a shade support.

3. In a lighting fixture, the combination of a lamp socket comprising a base and an 95 interiorly and exteriorly threaded lamp receiving shell, an interiorly and exteriorly threaded member adapted to screw over the lamp shell, and a shade holder adapted to screw over said last named member.

4. In a lighting fixture, the combination of a lamp socket comprising a base and an 100

interiorly and exteriorly threaded lamp receiving shell, an interiorly and exteriorly threaded supporting member adapted to screw over the lamp shell, a lamp shade, and 5 a shade holder adapted to screw over the supporting member and provided with a shoulder adapted to bear upon the interior of the shade to support the same.

In testimony whereof, I have hereunto set my hand and affixed my seal in the presence of the two subscribing witnesses.

ANTON MODRAY. [L.S.]
